UNITED STATES PATENT OFFICE.

JULIAN EVELYN CHURCH, OF PROVIDENCE, RHODE ISLAND.

WATCH FOB.

1,426,042.

Specification of Letters Patent. Patented Aug. 15, 1922.

Application filed April 14, 1922. Serial No. 552,802.

To all whom it may concern:

Be it known that I, JULIAN E. CHURCH, a citizen of the United States, and resident of Providence, in the county of Providence and State of Rhode Island, have invented 5 certain new and useful Improvements in Watch Fobs, of which the following is a specification.

This invention relates to watch fobs and 10 more particularly to a means for attaching the same to one's person.

An important object of this invention is to provide a watch fob wherein the attaching member of the same is formed from a 15 single length of wire formed with a plurality of bends which define parallel arms co-operating with each other to provide a series of open ended loops adapted to adjustably receive the ribbon of the fob whereby the 20 several loops formed by the ribbon may be varied in size as the occasion requires.

A further object of the invention is to provide a watch fob having simple means whereby the watch supporting loop may be 25 adjusted for supporting the watch in an upright position within the watch pocket.

A further object is to provide a watch fob of the class described which is of highly simplified construction, neat in appearance 30 and cheap to manufacture.

Other objects and advantages of the invention will be apparent during the course of the following description.

In the accompanying drawing, forming a 35 part of this application and in which like numerals are employed to designate like parts throughout the same,

Figure 1 is a perspective of the improved watch fob applied.

40 Figure 2 is a perspective of the improved watch fob detached.

Figure 3 is a longitudinal sectional view through the improved watch fob.

Figure 4 is a perspective of the improved 45 watch fob attaching and adjusting member.

Figure 5 is a perspective of a modified form of the invention.

In the drawing wherein for the purpose 50 of illustration is shown a preferred embodiment of the invention, the numeral 5 generally designates the adjusting and attaching member of the fob, which adjusting and attaching member is formed from a single length of wire formed with a plurality of 55 bends defining parallel arms 6 which cooperate in the formation of a series of open

ended loops. As illustrated in Figure 4, each loop formed by the several parallel arms 6 is open at one end while the other end is closed. In carrying out the invention, one end portion of the wire is allowed to remain straight to provide a shank 8 terminating in a hook 9 which may be engaged with the post or shank of an ornamental button 10 extended through the button hole 65 opening in the lapel of one's coat. Figure 1 illustrates the ornamental button or pin 10 applied to the lapel of the coat and the hook 9 may be readily and conveniently connected to the shank of the button whereby 70 to secure the improved fob to the lapel of the coat.

Figure 4 further illustrates that the lower terminal portion of the wire is bent upon itself to provide a closed loop 16 which 75 eliminates the point at the lower end of the wire and thereby prevents the ribbon generally designated by the numeral 20 from being torn or penetrated.

The upper portion of the ribbon is se- 80 cured to the uppermost arm 6 of the attaching and adjusting member as indicated at 21 by stitching or other suitable means and the ribbon is then extended through the next pair of arms to provide an ornament 85 supporting loop 25. The arms 6 on opposite sides of the loop 25 grip the ribbon and hold the same in an adjusted position so that the loop 25 will not be enlarged as the result of the weight of the ring 26. The ring 26 90 may be employed for supporting any desired ornament indicated by the numeral 28.

In carrying out the invention the ribbon is also passed rearwardly of the adjusting member and then downwardly to provide 95 the watch carrying loop 30 which is variable in size. The terminal portion of the ribbon is passed between and is securely gripped by a pair of the arms 6 so that the loop 30 will not be enlarged by the downward pulling of the watch or other article carried by the fob.

Figure 2 further illustrates that one end of the ribbon is arranged between the inner and outer folds of the watch carrying loop 105 30 and is partly concealed thereby.

In use the ornament carrying loop 25 is adjusted in length so that the ornament carried thereby will be disposed midway between the button hole in the lapel and the 110 pocket and the length of the watch carrying loop 30 is now adjusted so that the watch

will be supported in an upright position in one's pocket.

The improved watch fob is cheap to manufacture and may be readily and conveniently applied to one's coat and when in use does not in any way mar one's appearance and in fact adds considerably to it. The length of the loops 25 and 30 may be varied for use on different styles of coats and when the ribbon becomes worn a new one may readily be applied.

In carrying out the invention the shank 8 of the attaching and adjusting member may be formed with a bend 40 to which the button 42 may be soldered or otherwise secured. It will be seen that this form of the invention, as illustrated in Figure 5 differs from that illustrated in Fig. 4 in that the button is soldered directly to the shank 20 while in the form of the invention illustrated in the other figures the button is separate and apart from the shank.

Having thus described the invention, what I claim is:—

- 25 1. A watch fob comprising an attaching and adjusting member formed from a single length of wire provided with a plurality of bends defining parallel gripping arms one end portion of said length of wire being formed with a hook adapted for engaging the article to which the fob is connected, the other end of the wire being formed with a bend defining a closed loop, and a ribbon having one end portion permanently attached to one of the arms and passed between and gripped by the other arm and forming short and long ornament supporting loops.
- 30 2. A watch fob comprising an attaching and adjusting member formed from a single length of wire provided with a plurality of bends defining parallel gripping arms one end portion of said length of wire being

formed with a hook adapted for engaging the article to which the fob is connected, 45 the other end of the wire being formed with a bend defining a closed loop, a ribbon having one end portion permanently attached to one of the arms and passed between and gripped by the other arm and forming short 50 and long ornament supporting loops, and an article carrying ring connected to one of said ornament carrying loops.

3. A watch fob comprising a combined attaching and adjusting member formed 55 from a single length of wire formed with bends defining parallel gripping arms, one end portion of said wire being extended at right angles to said arms and formed with an attaching hook, said loops having their 60 ends open, and a ribbon having its upper end secured to the uppermost arm, said ribbon being passed between and gripped by said arms, and forming loops variable in length, the lower terminal portion of said 65 ribbon being confined between the inner and outer folds of one of said loops and concealed thereby.

4. A watch fob comprising a combined attaching and adjusting member formed 70 from a single length of wire formed with bends defining parallel gripping arms, one end portion of said wire being extended at right angles to said arms and formed with an attaching hook, said loops having their 75 ends open, a ribbon having its upper end secured to the uppermost arm, said ribbon being passed between and gripped by said arms, and forming loops variable in length, the lower terminal portion of said ribbon 80 being confined between the inner and outer folds of one of said loops and concealed thereby, and an article carrying loop connected to one of the loops of said ribbon.

JULIAN EVELYN CHURCH.
